UNITED STATES PATENT OFFICE.

CHARLES LORBER, OF LOUISVILLE, KENTUCKY.

COMBINATION KEY CASE.

Application filed October 26, 1926. Serial No. 144,288.

This invention relates to a combination of a bill fold, a card case and key case and which I preferably term a combination key case.

5 One object of the invention is to provide a novel case of this character wherein access may be had to cards contained therein without opening either the key case portions or the bill fold portion.

10 A second important object of the invention is to provide an improved article of this class combining in itself a bill fold, pockets for cards and a key case, thus serving to eliminate the necessity of a person carrying a bill fold, a key case, and an identification or calling card case as separate articles.

15 A third important object of the invention is to provide a novel construction of such a case employing but few separate pieces of leather or other suitable material in its manufacture, and these being secured together simply so that the case may be manufactured very economically.

20 With the above and other objects in view as will be hereinafter apparent, the invention consists in general of certain novel details of construction and combinations of parts hereinafter fully described, illustrated in the accompanying drawings and specifically claimed.

25 In the accompanying drawings like characters of reference indicate like parts in the several views, and:

Figure 1 is a top edge view of one form 30 of the invention.

Figure 2 is a view showing the device opened fully and looking at the inside.

Figure 3 is a perspective view showing the three main parts of the device disassembled.

35 Figure 4 is a section on the line 4—4 of Figure 2.

Figure 5 is a top edge view of a second form of the device.

Figure 6 is a view of this form similar to Figure 2 but partly broken away to disclose one of the card pockets in this form.

Figure 7 is a partly disassembled perspective view of certain of the parts in this form.

Figure 8 is a section on the line 8—8 of 50 Figure 6.

Figure 9 is an enlarged detail view of part of a key holder suitable for use herewith.

In the form of the invention shown in Figures 1 to 4 inclusive the article has its 55 body constructed of three pieces of suitable

material, such as leather or the like and one of these pieces is rectangular in outline and constitutes a back having end sections 10 and a central section 11 to which the end sections are connected integrally by thin portions 12 60 providing places at which the back may be folded to bring the end sections in overlapping relation. These parts 12 may be thinned down from the normal thickness of the material in any of the usual ways such 65 as by cutting, skiving or sandpapering.

In front of this back lies an intermediate strip having end sections 13 and a central section 14, defined from the end sections by deep notches or gores 15 which lie in front 70 of the thinned portions 12 and extend downwardly from the top of the intermediate strip. This intermediate strip is of the same length and height as the back.

75 In front of the intermediate strip lies the liner which is, in general, of the same form and dimensions as the intermediate strip, having end sections 16, a central section 17 and notches 18. However, the central section also has an extension 19 on its upper edge which is provided with a series of key holder slots 20 and which, in the finished article, is folded down on the central section 17 and there secured by one or more lines 80 of stitching 21 as shown in Figure 2.

85 In assembling the back, the intermediate strip and liner are placed together with their bottom and end edges coinciding and these edges are then secured by a stitch line 22 thus leaving the top edges of the several parts free from each other. The notched portions of the intermediate strip and liner are stitched together by stitch lines 23 running close to the edges of the notches and the space between the intermediate strip and liner is thus divided into three pockets 24 open at the top, the space between the intermediate strip and back being uninterruptedly open at the top throughout its length so as to accommodate bills in unfolded condition. 90 Snap button parts 25 are, however, preferably provided at the top of this bill pocket 26 so that the pocket may be closed against bills placed therein accidentally falling out.

105 In the form of the invention shown in Figures 5 to 8 inclusive there is provided a back piece 27 of elongated rectangular outline and made from leather or other suitable material. On the front or inner face of this piece there is provided adjacent each end a 110

2
pocket 28 having its side and bottom edges secured to the back by stitching 29. Each pocket is provided in its upper edge with a finger space or notch 30. This form is also 5 provided with a liner 31 which has on the central portion of its upper edge an extension 32 provided with a series of slots 33. The extension is folded onto the inner face of the liner and there secured by stitches 34 10 while the liner is secured to the back by a stitch line 35 extending along the sides and bottoms of these parts. There are thus the card pockets 36 and the long continuous bill pocket 37 which latter may be closed by the 15 snap button parts 38.

In the form shown in Figure 2 there is provided a slot 42 affording access to the pocket 24, the pocket being closed by a stitch line 43 above this slot. This pocket may be 20 used for an identification card, inserted through the slot and having its upper edge turned down to lie outside the pocket for convenience in withdrawal.

In each case the key holders 39 have their 25 shanks extended through the slots 20 or 33 and are retained by some suitable securing means, preferably flexible in character though this is not essential. As an example of such means the construction shown in 30 Figure 9 may be used wherein each shank extends into a hollow ball 40 and is provided with a head therein, the balls being connected by headed links 41 and all parts being swivelly movable relative to each 35 other. Obviously, other means may be used to secure the key holders to the device.

The device is used as in any ordinary bill fold and card case with the key holders carrying such keys as may be desired. It is 40 to be noted that the cards, in both forms are accessible without opening the case and the key holding part may be opened without opening the bill fold.

There has thus been provided a simple and 45 efficient device of the kind described and for the purpose specified.

It is obvious that minor changes may be made in the form and construction of the invention without departing from the material spirit thereof. It is not, therefore, desired to confine the invention to the exact 50 form herein shown and described, but it is desired to include all such as properly come within the scope claimed.

Having thus described the invention, what 5 is claimed as new, is:

1. The combination in a key case of a key supporting member provided with closure means to cover the keys from access, a back piece secured to the bottom and side edges 60 of said member and free at the top thereof to form a bill pocket which is freely accessible with the key case closed, and other pockets located between said member and the back piece and likewise freely accessible 65 with the key case closed.

2. In a key case, a back piece, an intermediate strip of the same length and height as the back piece, and a key supporting liner of like dimensions, said back piece, intermediate strip and liner being united at the side and bottom edges leaving the top edges freely separable, and stitching uniting the intermediate piece and liner at spaced intervals to divide the space between the intermediate strip and liner into a plurality of pockets. 70

3. In a key case, a back piece, an intermediate strip of the same length and height as the back piece, and a key supporting liner of like dimensions, said back piece, intermediate strip and liner being united at the side and bottom edges leaving the top edges freely separable, said intermediate strip and liner having deep notches extending downwardly from their top edges in registering alinement, and stitching extending around said notches to divide the space between the intermediate strip and liner into a plurality of pockets. 80

4. In a key case, a back piece, an intermediate strip of the same length and height as the back piece, and a key supporting liner of like dimensions, said back piece, intermediate strip and liner being united at the side and bottom edges leaving the top edges freely separable, said intermediate strip and liner having deep notches extending downwardly from their top edges in registering alinement, and stitching extending around said notches to divide the space between the intermediate strip and liner into a plurality of pockets, said back piece having thin areas alined with said notches to assist in folding the case readily between said pockets. 90

In testimony whereof I affix my signature.

CHARLES LORBER.
